UNITED STATES PATENT OFFICE.

GEORGE K. CUMMINGS, OF NEW YORK, N. Y.

DESIGN FOR A PRISM-WINDOW.

SPECIFICATION forming part of Design No. 29,809, dated December 13, 1898.

Application filed August 15, 1898. Serial No. 688,632. Term of patent 7 years.

To all whom it may concern:

Be it known that I, GEORGE K. CUMMINGS, a citizen of the United States, residing at New York, in the county and State of New York, 5 have invented and produced a new and useful Design for Prism-Windows, of which the following is a specification.

My invention relates to a new design for prism-windows, and is illustrated in the accompanying drawings, in which—

Figure 1 is an elevation or front view of a prism-window embodying my said design, and Fig. 2 is a vertical cross-section through the middle of the window.

5 The design consists of a window comprising a number of triangularly-shaped panes or

lights of prism-glass arranged as shown. The parallel cross-lines of Fig. 1 represent the angular edges of the glass prisms. The heavier doubled lines of the drawings represent the 26 framework.

I claim—

The design for a prism-window as herein shown and described.

In testimony whereof I have signed my 25 name to this specification in the presence of two subscribing witnesses.

GEORGE K. CUMMINGS.

Witnesses:

EDWIN SEGER,
SIDNEY MANN.
